UNITED STATES PATENT OFFICE

WALLACE PATTEN COHOE, OF RIVERDALE-ON-THE-HUDSON, NEW YORK, ASSIGNOR TO
WALLACE P. COHOE & COMPANY, A CORPORATION OF NEW YORK

CAP CLOSURE

Application filed June 18, 1926. Serial No. 116,824.

My invention relates to an improved form of closure for sealing the openings in bottles, etc., but it has relation especially to milk bottle covers or closures.

5 The present invention is an improvement over the previous inventions as set forth in my applications for Letters Patent entitled Novel closure cap, Serial No. 679,906, filed December 11, 1923, and Closure cap for containers, Serial No. 715,792, filed May 26, 10 1924.

15 The object of my invention is to provide a closure of the character above referred to, which is more readily applicable to a container to which it is to be applied, and which can be applied more quickly and effectually to the same. More particularly, the object of my invention is to avoid the slow drying of the wet cap where the cap, being made out 20 of a flat disk, has, when formed therefrom, a thick body of the material at the turned-over edge, causing an accumulation of moisture therein which delays the drying of the cap unnecessarily. A further object is to 25 apply a protective material to the skirt of the cap so as to further diminish the amount of moisture to be removed therefrom in the final drying of the cap. Further objects of my invention will appear from the detailed description of the same hereinafter.

30 While my invention is capable of being carried out in many different ways, by way of illustration I have shown only one way of carrying out the same in the accompanying drawings in which—

Figure 1 is a side elevation of a milk bottle carrying a cap made in accordance with my invention; and

40 Figure 2 is a vertical section through the same.

In the drawings I have shown a milk bottle 1 having an opening 2 at the top of the same which is closed by a cap 3 having a depending skirt or flange portion 4 surrounding the edge of the mouth of the bottle. It 45 will be noted that the depending flange or skirt 4 has at its lower edge a series of serrations or indentations 5 to enable the cap to more effectively contract against the edge of 50 the mouth of the bottle and, also, to prevent

the formation at this part of the cap, of a thickened portion of the paper of the cap due to its having been formed from a flat disk, and, furthermore, to obviate as far as possible the accumulation of moisture at this 55 point in the cap, which would be difficult to remove. If desired, furthermore, I may impregnate or coat this part or the whole of the cap 3 with a waterproofing material such as a waxy or resinous body. When 60 such waterproofing material is applied this is preferably applied merely to the skirt or flange 4 by dipping the same into a composition comprising ordinary rosin or colophony in a fused condition, before the cap is applied to the bottle. Preferably, also, the 65 waterproofing material will have become dry or hard before the cap has been applied to the bottle. Thereafter, the cap 3, which is made of paper, fiber, or similar material, will be coated either before its application to the bottle or after, and either on the inside or outside, or both, with an aqueous cellulose solution. The aqueous cellulose 70 solution is preferably a solution of viscose 75 but may, if desired, be any other aqueous solution of cellulose as, for example, a cuprammonium solution or a zinc chloride solution. Furthermore, it will be understood that the entire cap may be so treated with 80 the aqueous cellulose solution, or only the depending portion 4 which surrounds the edge of the mouth of the bottle. The cap 3, after having had the aqueous cellulose solution applied as above, is applied to the bottle 85 either before or after the said solution of cellulose has been coagulated by any one of the well-known methods. Thereupon, the film of aqueous cellulose solution will contract and cause the cylindrical portion of the 90 cap to contract likewise. As a result a tight closure of the bottle, or other container, is effected and this will retain the contents of the milk undisturbed and free from tampering until it reaches the ultimate consumer. 95 Inasmuch as the aqueous solution would be affected by water, however, in this condition, it is desirable to subject it to heat so that water will not affect the same. This I accomplish by applying any desired form of 100

heating tool to the cap or around the edge of the same, but especially over the skirt portion 4, said tool being heated to a temperature of at least 115 to 130° C. As a result, 5 not only is the waxy or resinous material molded to fit the neck of the bottle so as to tend to hold the cap in position, but the aqueous cellulose solution, as a result of the heat, loses a sufficient amount of water to 10 form a horny substance incapable of there- after being affected by water. It will be understood, however, that in the case where the waxy or resinous material has been applied to the skirt portion 4 of the cap it is 15 desirable to have the whole flange or skirt of the cap dipped in or coated by the aqueous cellulose solution in order to completely cover the waxy or resinous coating so as to prevent the waxy or resinous material from 20 adhering to the bottle and to the heating tool which is applied to the outside of the same. Furthermore, it is to be understood that it is particularly desirable, that where the waxy or resinous material has been applied 25 to the skirt portion 4 of the cap, to have the aqueous cellulose solution extend to a point at least above the upper edge of the coating of waterproofing material so as to completely enclose the same and to obtain 30 a good bond between the cellulose solution and the paper of the cap. In any event it will be understood that the serrated edge 5 of the cap will have its serrations filled with the aqueous cellulose solution so that, as a 35 result, the portion 4 of the cap is formed into a slotted contractual ring which grips the bottle and forms a tight closure therewith. This whole procedure materially shortens the time required for completely applying 40 the cap to the containers.

It will be understood, however, that, if desired, in the case where the waterproofing coating of waxy or resinous material has been applied, the serrations 5 of the cap may 45 be omitted, in which case the plastic skirt of the cap is molded to fit the bottle by the hot tool and the cellulosic coating prevents the resinous plastic material from sticking to the bottle or to the tool.

50 With this form of closure, in order to gain access to the bottle it will be necessary to destroy the closure to a greater or less extent.

While I have described my invention above in detail I wish it to be understood that many 55 changes may be made therein without departing from the spirit of the same.

I claim:

1. A container closure having a slotted en- 65 gaging portion coated with an aqueous cel- lulose solution extending between the slits therein that has been coagulated, said en- gaging portion being contracted by the cel- lulose of the solution extending between the slits to seal the container.

2. A container closure having a slotted en-

gaging portion coated with an aqueous cel- 70 lulose solution extending between the slits therein that has been coagulated and ren- dered partially anhydrous and horny in char- acter so as to be unable to expand when wetted, said engaging portion being contract- ed by the cellulose of the solution extending between the slits to seal the container.

3. A circular bottle cap having a slotted en- 75 gaging portion coated with an aqueous cel- lulose solution extending between the slits therein that has been coagulated, said engag- ing portion being contracted by the cellulose of the solution extending between the slits to seal the container.

4. A circular bottle cap having a slotted en- 80 gaging portion coated with an aqueous cel- lulose solution extending between the slits therein that has been coagulated and rendered partially anhydrous and horny in character so as to be unable to expand when wetted, said engaging portion being contracted by the cellulose of the solution extending between the slits to seal the container.

5. A container closure having a slotted en- 90 gaging portion coated with a viscose solution extending between the slits therein that has been coagulated, said engaging portion being contracted by the cellulose of the solution extending between the slits to seal the con- 95 tainer.

6. A container closure having a slotted en- 100 gaging portion coated with a viscose solution extending between the slits therein that has been coagulated and rendered partially an- hydrous and horny in character so as to be unable to expand when wetted, said engag- ing portion being contracted by the cellulose of the solution extending between the slits to seal the container.

7. A circular bottle cap having a slotted en- 105 gaging portion coated with a viscose solution extending between the slits therein that has been coagulated, said engaging portion being contracted by the cellulose of the solution ex- 110 tending between the slits to seal the contain- er.

8. A circular bottle cap having a slotted en- 115 gaging portion coated with a viscose solution extending between the slits therein that has been coagulated and rendered partially an- hydrous and horny in character so as to be unable to expand when wetter, said engag- ing portion being contracted by the cellulose of the solution extending between the slits to 120 seal the container.

9. A container closure having a slotted en- 125 gaging portion coated with a waterproofing material and an aqueous cellulose solution extending between the slits therein that has been coagulated, said engaging portion being contracted by the cellulose of the solution extending between the slits to seal the container.

10. A container closure having a slotted 130

engaging portion coated with a waterproofing material and an aqueous cellulose solution extending between the slits therein that has been coagulated and rendered partially anhydrous and horny in character so as to be unable to expand when wetted, said engaging portion being contracted by the cellulose of the solution extending between the slits to seal the container.

10 11. A circular bottle cap having a slitted engaging portion coated with a waterproofing material and an aqueous cellulose solution extending between the slits therein that has been coagulated, said engaging portion being contracted by the cellulose of the solution extending between the slits to seal the container.

15 12. A circular bottle cap having a slitted engaging portion coated with a waterproofing material and an aqueous cellulose solution extending between the slits therein that has been coagulated and rendered partially anhydrous and horny in character so as to be unable to expand when wetted, said engaging portion being contracted by the cellulose of the solution extending between the slits to seal the container.

20 13. A container closure having a slitted engaging portion coated with a waterproofing material and a viscose solution extending between the slits therein that has been coagulated, said engaging portion being contracted by the cellulose of the solution extending between the slits to seal the container.

25 14. A container closure having a slitted engaging portion coated with a waterproofing material and a viscose solution extending between the slits therein that has been coagulated and rendered partially anhydrous and horny in character so as to be unable to expand when wetted, said engaging portion being contracted by the cellulose of the solution extending between the slits to seal the container.

30 15. A circular bottle cap having a slitted engaging portion coated with a waterproofing material and a viscose solution extending between the slits therein that has been coagulated, said engaging portion being contracted by the cellulose of the solution extending between the slits to seal the container.

35 16. A circular bottle cap having a slitted engaging portion coated with a waterproofing material and a viscose solution extending between the slits therein that has been coagulated and rendered partially anhydrous and horny in character so as to be unable to expand when wetted, said engaging portion being contracted by the cellulose of the solution extending between the slits to seal the container.

40 In testimony that I claim the foregoing, I have hereunto set my hand this 14th day of June, 1926.

WALLACE PATTEN COHOE.
